UNITED STATES PATENT OFFICE.

MYRON PENN LAUGHLIN, OF BATH, MAINE.

ELECTRIC TELEMOtor APPARATUS.

Application filed March 2, 1922, Serial No. 540,656. Renewed March 18, 1924.

To all whom it may concern:

Be it known that I, MYRON P. LAUGHLIN, a citizen of the United States, and a resident of Bath, in the county of Sagadahoc and State of Maine, have invented certain new and useful Improvements in Electric Telemotor Apparatus, of which the following is a specification.

My present invention concerns an electric telemotor apparatus for enabling a moving part to be effectively controlled from a distance, and aims to provide means in which the control may be effected by the use of a circuit or circuits which shall be free from contacts or circuit making and breaking devices.

The invention comprises the novel system of electric distribution and control and the means therefor, as hereinafter described, my said invention being defined by the appended claims.

My invention is illustrated in the accompanying drawings, in which:—

Figure 1 is a diagrammatic view of a ship's steering telemotor apparatus embodying my invention, the moving coils of the transmitter and follow up induction regulators being shown on center line, and the steering motor being in stationary or inactive condition, arrows indicating wires in which current is flowing, and lack of arrows indicating where no current is flowing.

Fig. 2 is a similar view illustrating the circuits only, the moving coil of the transmitter having been turned from center line to the right and the direction of resulting currents being indicated by arrows, the follow up regulator having not started to move, or being just ready to start.

Fig. 3 is a view similar to Fig. 2, with the coil of the follow up regulator turned to current neutralizing or bucking position. Fig. 4 is a detail view of the follow-up lever.

While I have, for convenience, selected a ship's steering gear as suitable for illustrating the manner of embodiment and use of my invention, it will be understood that it is not limited to such use, but is adapted as well for the control from a distance of a motor designed to operate any moving part.

Referring to reference characters to this drawing, the numeral 1 designates a rudder stock or post operatively connected to the

plunger 2 of the double hydraulic ram, the cylinders of which are designated 2^a and 2^b respectively. The fluid for operating the ram is supplied under the requisite pressure from a non-reversible pump 3 driven by a main motor 4, the proper distribution of motor fluid being effected by the reverse valve 5 which is operated by the follow-up lever 6 in the manner well understood by those skilled in the art.

The arrangement of parts thus far described is, or may be, similar to that shown in Letters Patent of the United States granted to C. E. Paine on the 8th day of July, 1919, No. 1,309,076, and is shown for convenience of illustration only.

The follow up lever 6 is operated by a screw shaft 7 which engages a nut 8 having wings which engage slots 6^a in a bifurcated portion of the follow up lever, the intermediate portion of the lever being connected to the reversing valve stem 5^a and the opposite end connected with the plunger by a slotted connection indicated at 6^b.

Screw 7 is driven from a valve control electric motor (preferably D. C.) through reducing gearing 9, 10, and the screw shaft may be continued to an auxiliary stand, and provided with means for hand operation (not shown) in case of trouble with the electric apparatus.

The valve control electric motor is indicated by the numeral 11, the field and armature being supplied with current by the conductors as shown. The armature shaft 90 is connected by gears 12, 13 with a shaft 14 which carries fast thereon a worm 15 meshing with a worm gear segment 16 attached to or connected with the moving coil or secondary 17^a of the follow up induction regulator 17.

The shaft of motor 11 may be provided with a magnetic brake indicated conventionally at 18.

The numeral 19 designates the trick 100 wheel, the shaft of which carries fast thereon a worm 20 meshing with a worm gear segment 21 which in turn operates in suitable manner, as by means of bevel gears 22 and shaft 23, the moving coil or secondary 24^a of the transmitting induction regulator 24.

The transmitter and follow up regulators are connected with each other by the lines or conductors indicated by the words 110

"Line", "Common", and "Control" respectively as will hereinafter more clearly appear, the "Line" and "Common" conductors being connected to a suitable source of 5 alternating current.

Said conductors are also connected with a polarized relay 25, the armature of which carries a switch arm 26.

Normally, and with the parts in position 10 shown in Fig. 1, for example, the path of alternating current is as indicated by the arrows *a*, *b*, the secondaries of the regulators being on neutral, no current is induced in the "control" wire and coil *g* of 15 relay 25 not being excited takes a neutral position in field *f*, the switch arm 26 is maintained in open position, assisted by adjustable springs 26^a which prevent contacts to motor circuit being made when, or if, 20 alternating current supply is discontinued.

Switch arm 26 controls the flow of direct current through the armatures of motor control relay switches 27 and 28, both switches being shown in Fig. 1 in open 25 position, though each is making contact which affords path for starting current when the other switch is closed, in such open position the armature of the motor being short circuited, effecting a quick stop 30 of the motor.

Referring now to Fig. 2, in which the moving coil or secondary of the transmitter has been turned to the right or in a clockwise direction by the trick wheel and magnetic lines of force are cut and current is 35 instantly induced therein, the direction of current being indicated by arrows *c* from the secondary to "common" wire, to the secondary of the follow up regulator, then 40 by "control" wire in direction of arrow *c'* to armature coil *g* of polarized selector relay 25, returning as indicated by arrow *c* over the "control" wire to secondary of the transmitter. The energizing of armature coil *g* gives it a polarity which seeks the unlike poles in its magnetic field, and hence operating in a manner analogous to a polarized relay. This causes switch arm 45 26 to make contact on the direct current circuit, the path being from positive supply wire through wire *d*, contacts *d'*, *d*², wire *d*³, magnet coil *d*⁴, and wire *d*⁵ back to the negative.

Magnet *d*⁴ having thus been energized, 55 switch or circuit closer 27 is moved from the position shown in Fig. 1 to that shown in Fig. 2, which closes the circuit through the motor, the path of the current being through positive line *e*, armature or switch contacts *e'*, *e*², line *e*³ to motor armature, line *e*⁴, armature or switch contacts *e*⁵, *e*⁶, and line *e*⁷, *e*⁸ to negative line. In this view 60 the motor is indicated as just starting and hence the follow up regulator has not been moved. The operation of the motor through 65

the gearing, screw shaft and follow up lever 6 hereinbefore described operates the reversing valve to admit fluid under pressure to the ram which turns the rudder stock, the follow up lever 6 acting in the 70 manner well understood by those skilled in the art.

At the same time the rotation of the motor armature through the worm gearing 16, 17 swings the follow up secondary in the 75 direction of the arrow, and, supposing the movement of the trick wheel and transmitter to have stopped, the follow up secondary will continue to move until it has reached the same degree of angularity as 80 the transmitter secondary when the current will be neutralized, and, since no current then flows in the control wire, the conditions shown and described in connection with relay 25 in Fig. 1, are restored. 85

As will be obvious, however, continued movement of the trick wheel will cause the transmitter secondary to keep ahead, so to speak, of the follow up regulator, so that any desired degree of movement may be 90 imparted to the rudder.

Obviously if the trick wheel is moved in the opposite direction, this will cause the transmitter secondary to swing over in a counter clockwise direction. This causes 95 the current induced in the transmitter secondary to flow by "control" wire through coil *g*, to the secondary of the follow up regulator, and by "common" line back to the transmitter secondary. 100

The polarity of coil *g* is now reversed from that of Fig. 2 and electric connection is made between contacts *d'* and *d*⁶. The resulting direct current flow is from the positive line through line *d*, contacts *d'*, *d*⁶, line *d*⁷, magnet coil *d*⁸, and lines *d*⁹, *d*¹⁰ to negative. Switch arm 28 being attracted, the path of the motor current is from positive line through line *e*, switch contact *e*⁶, line *e*⁴ to motor armature, and thence 110 by line *e*³, switch contact *e*', and line *e*² to negative line. This gives movement in a reverse direction to the motor and follow up secondary as indicated by the respective 115 arrows.

In Fig. 3, I have shown the secondary of the transmitter in the position it would assume if it had thus moved in a counter clockwise direction in response to a movement of the trick wheel in the opposite 120 direction to that shown in Fig. 2. I have also indicated in Fig. 3 (by arrow *c*), the direction of the induced current under these circumstances, viz., from secondary through the "control" line to coil *g*. When the secondary of the follow up regulator starts to turn, the strength of induced current is proportional to the angularity, but when the travel of the follow up secondary 125 has caused it to reach a degree of angu- 130

larity equal to that of the transmitter secondary, as shown in Fig. 3, the strength of induced current is equal.

The path of the bucking up or neutralizing current is, as shown by arrows, from the follow up secondary through line c' , to coil g , when it will be opposed to current from the transmitter and hence no current will pass through coil g which will move to neutral position, opening the switch contacts on the direct current circuits, and stopping the motor.

It will be evident that since a balanced electrical circuit condition indicates that the ship's rudder or corresponding movable part has taken a position which corresponds to that of the trick wheel, while an unbalanced condition indicates that there is a lack of correspondence in the position of said parts, any instrument which will indicate a state of balance or unbalance will serve as an indication of the action of the telemotor apparatus and such an instrument may be a voltmeter 30 connected up as shown.

The instrument here described would indicate only during a difference in the angles of transmitter and follow-up, and would show zero at any angle of rudder after a balanced circuit was attained. Also it is evident that a raised lowered or normal voltage taken from the line and control wires has a direct relation to the angularity of movement of both the transmitter and follow-up and any instrument such as a voltmeter 30 connected up as shown will indicate the action of the telemotor apparatus and supply a rudder angle indicator. For example with connections made to line and control wires as shown, the circuit shunted is the primary and secondary windings in series as shown by arrows Fig. 1.

In this figure no current being induced in the secondary, the reading will be equal to the supply minus a slight resistance drop.

In Fig. 2 current directions are opposed and the meter will indicate a bucked or lowered voltage.

In Fig. 3, a boosted or raised voltage is indicated and the follow up having changed to a corresponding angle has raised the meter reading, thus affording an indicator of the movement of the follow-up.

Since the alternating current control arrangement described is contactless, there are no "steps" in its operation. The system will unbalance upon any difference in relative position between the trick or steering wheel and the rudder which eliminates the difficulties due to a limited number of steering positions, the sensitivity of the apparatus depending upon the sensitiveness of the actuating device, which, with a contactless alternating current control such as hereinbefore described, is very great.

It will be understood that I do not limit

myself to the manner shown of applying power to the rudder for obviously, if desired, the motor shown as operating the valve could be an A. C. or D. C. motor of sufficient power to operate the rudder by direct drive, or any form of power transmitting connections could be used.

It will also be understood that I do not limit myself to any particular form of induction regulators, or relays, nor to the particular arrangement of circuits disclosed, as the same could be varied in many ways without departing from the spirit of my invention.

For example, instead of regulators of the type shown I might use regulators of the A. C. balanced reactance bridge type, to wit, a system of balanced impedances with cores equal in all the coils, wherein, when the impedance valves are equal no current will flow in the control circuit, but motion of the trick wheel produces unbalance in the system and causes a current to flow in the motor armature circuit, the follow up restoring the balance and stopping the telemotor in a position corresponding to where the trick wheel has been stopped.

It will further be obvious that in place of the regulators shown, two phase and three phase motors could be provided to be started and reversed by direct connection to the controlled circuit, in which event the phase difference produced by the action of the induction regulators acting in the phase windings of a two or three phase squirrel cage induction motor, would cause the motors to stop or reverse as the case might be.

Again it is obvious that variable condensers or condensers combined with reactances may be substituted for the induction regulators. In fact it should be understood that by the term induction regulator I mean to include any form of contactless current variator means for changing the current.

Having thus described my invention, what I claim is:

1. In an electric transmission system, a pair of induction regulators each comprising stationary and movable coil portions, a contactless closed circuit including like coil portions of each of the regulators, means for producing a variating current therein, the other coil portions being each electrically connected to one of the lines of said circuit, and having a conductor joining points of balanced potential on said other coil portions when the latter are in balanced position, said conductor including means responsive to current interchange.

2. In an electric transmission system, a pair of induction regulators, each comprising stationary and movable coil portions, a contactless closed circuit including like portions of each of the regulators, means for

- producing a variating current in said circuit, the other coil portions being each electrically connected to one of the lines of said circuit, and having conductors joining 5 points of balanced potential on said other coil portions, means for moving the movable coil portion of one of the regulators, means responsive to current interchange included in said conductor, said last named 10 means in turn controlling the movement of the movable coil portion of the other regulator, which in turn controls the movement of the means responsive to current interchange.
- 15 3. In an electric transmission system, a transmitter and a receiver, each comprising stationary and movable coil portions, a contactless closed circuit including the stationary coil portions, means for producing 20 a variating current therein, said movable coil portions being electrically connected to one of the lines connecting the stationary coil portions, and having a conductor joining points of balanced potential 25 on the movable coil portions when the latter are in balanced position, said conductor including means responsive to current interchange.
- 30 4. In an electrical transmission system, a transmitter and a receiver, each comprising field windings and a movable armature, two circuit portions having one conductor in common extending between said transmitter and receiver, and both including some of 35 said windings, means for causing a constant alternating current to flow in one portion of said circuit, and means at the transmitter for setting up a current in the other portion of the circuit, whereby the resultant field 40 generated by said windings may be altered, said common conductor including means responsive to current interchange.
- 45 5. In an electrical transmission system, a transmitter and a receiver, each comprising stationary field windings and a movable armature coil, conductors connecting said fields, means for causing a constant alternating current to flow in said conductors, a third conductor connected to the windings 50 of said armature coils, said armature coils each being in turn connected to one of said first named two conductors, means for moving the transmitter armature coil relative to its field, and means responsive to current interchange included in said third conductor, said last named means in turn controlling 55 the movement of the receiver armature coil.
- 60 6. In an electric transmission system, the combination with a part to be moved, of a controlling mechanism therefor, including a transmitter and receiver, each comprising stationary field coils and a movable armature coil, conductors connecting said field coils, means for impressing a constant alternating current in said conductors, a third 65 conductor connected to the windings of said armature coils, said armature coils each being in turn connected to one of said first named conductors, means for moving the transmitter armature coil relative to its field, and means connecting the other movable armature coil to the part to be moved, and means responsive to current interchange included in said third conductor, and in turn controlling the part to be moved. 75
7. In an electric transmission system, the combination with a part to be moved, of controlling mechanism therefor, comprising an A. C. circuit, induction regulators normally connected to said circuit in opposed phase relation, each regulator having stationary and movable members, means for moving one of said movable members, and means operatively connecting the other of said movable members to said part to be moved. 80
8. In a telemotor apparatus, the combination with an electric motor operatively connected to a movable device, a circuit for said motor including electro-magnetically actuated switch mechanism, an A. C. circuit including an electro-magnet controlling the operation of said switch mechanism and induction regulators each having stationary and movable members, normally connected to said circuit in opposed phase relation and having means for adjusting the angularity between the members, one of said regulators being manually adjustable and the other being operatively connected to said rotor. 85
9. In a telemotor apparatus, a reversible driving motor, switch controlling mechanism therefor, an A. C. circuit controlling the operation of said mechanism, induction regulators normally connected in opposed phase relation in said circuit, said regulators having fixed and rotor members, and means under manual control for alternately varying the angular relation of said rotor members to thereby control the reactance effects of said regulators in said A. C. circuit. 90
10. In a telemotor apparatus, the combination with a part to be moved of an electric motor for moving said part, a motor circuit for said motor including controlling and reversing switch means, a closed A. C. circuit including a control line, a polarized relay included in said control line arranged to control said switch means, a moving coil induction regulator for said A. C. circuit, adapted when moved to induce current in said control line and operate said relay, and a follow up induction regulator having a coil arranged to be moved in unison with the motor and when so moved to induce a counter current in said control line to neutralize said relay. 105
- In testimony whereof, I affix my signature.
- MYRON PENN LAUGHLIN.
